No. 628,852.

Patented July 11, 1899.

F. REESE.

THILL COUPLING.

(Application filed May 1, 1899.)

(No Model.)

UNITED STATES PATENT OFFICE.

FREDERICK REESE, OF EUTAW, ALABAMA.

THILL-COUPING.

SPECIFICATION forming part of Letters Patent No. 628,852, dated July 11, 1899.

Application filed May 1, 1899. Serial No. 715,162. (No model.)

To all whom it may concern:

Be it known that I, FREDERICK REESE, a citizen of the United States, residing at Eutaw, in the county of Greene and State of Alabama, have invented a new and useful Thill-Coupling, of which the following is a specification.

This invention relates to thill-couplings, and has for its object to provide simple and improved means for preventing longitudinal displacement of the thill-bolt and rattling thereof.

To this end the present invention consists in the construction and arrangement of parts, as will be hereinafter more fully described, shown in the accompanying drawings, and particularly pointed out in the appended claims.

In the drawings, Figure 1 is a perspective view of the improved thill-coupling. Fig. 2 is a transverse sectional view taken through the thill-bolt. Fig. 3 is a longitudinal sectional view on the line $x-x$, Fig. 2. Fig. 4 is a detail perspective view of the antirattler-spring and bolt-lock.

Corresponding parts are designated by like reference characters in all the figures of the drawings.

Referring to the accompanying drawings, 30 Fig. 1 designates an ordinary axle-clip having the usual spaced bearing-ears 2 and the tie-bar 3, whereby the clip may be fastened upon an axle 4. The thill-iron 5 is provided with an eye 6, which is adapted to be located between the ears 2 and connected thereto by means of a smooth bolt 7, passing loosely through the eye and the opposite bearing-ears. One end of the bolt is provided with a head 8, adapted to rest flush against the outer face of one of 40 the bearing-ears, and near the opposite end of the bolt is provided a circumferential groove 9, which latter end of the bolt is adapted to project beyond the outer face of the opposite bearing-ear.

45 The means for locking the bolt against longitudinal displacement is shown in detail in Fig. 4 and comprises a substantially U-shaped spring 10, formed from a single length of flat spring metal bent intermediate of its ends to 50 provide the U shape. The upper member or side 11 of the spring is provided with suitable bolt-openings 12, adapted to receive the op-

posite ends of the axle-clip, whereby the said side 11 may be clamped against the under side of the axle by means of the tie-bar 3. The 55 upper free end of the side 11 is extended longitudinally outward beneath and beyond the bearing-ears 2 and then bent back upon itself, forming the antirattler-spring tongue 13, having its free extremity flared slightly upward, 60 located between the bearing-ears and adapted to bear upwardly against the thill-eye 6. The lower side of the U-shaped spring is also extended forward beyond the bearing-ears and bent backward upon itself, as at 14, and the 65 free extremity of the bend is provided with an offset upstanding arm 15, adapted to engage the outer face of one of the bearing-ears 2. This arm is provided at its upper end with a longitudinal slot 16, opening outward 70 through the upper end of the arm and inclined upwardly and rearwardly toward the axle. As indicated in Figs. 1 and 3, the arm 15 is adapted to receive the grooved or reduced portion 9 of the thill-bolt within the slot 16, 75 so that the outer shoulder 17 of the bolt may engage the opposite sides of the slot, and thereby prevent the bolt from being displaced longitudinally from the thill-eye and the bearing-ears 2. It will be understood that the 80 arm 15 is effectually held in engagement with the reduced portion of the thill-bolt by means of the lower side or member of the U-shaped spring 10, and the slot is inclined rearwardly for the purpose of facilitating the engagement 85 of the slotted arm with the thill-bolt.

It will be noted that the construction, as hereinbefore described, provides an antirattler-spring and a locking-arm for the thill-bolt, all formed from a single piece of metal, 90 which is positively connected to the axle-clip, so as to prevent possible loss of either of the parts.

The present invention may be readily applied to any of the common forms of thill-couplings without altering any part thereof, and by the employment of the device the thill-bolt is effectually locked against accidental displacement and rattling of the thill-arm or bolt within the bearing-ears is effectually prevented. Also, the antirattler-spring tongue 13 and the upstanding arm 15 are entirely independent of each other, being carried by the individual ends of the U-shaped 95 100

spring 10, so that the arm 15 may be disengaged from the bolt 7 without moving or otherwise interfering with the antirattler-spring.

5 Changes in the form, proportion, size, and the minor details of construction within the scope of the appended claims may be resorted to without departing from the spirit or sacrificing any of the advantages of this invention.

10 What I claim is—

15 1. In a thill-coupling, the combination with an axle-clip having opposite bearing-ears, a thill-iron, and a thill-bolt, of a substantially U-shaped spring having its upper side connected to the ends of the clip, the forward free end of said side being rebent across its upper face and forming an antirattler-spring tongue engaging the thill-iron, and the lower side of the U-shaped spring having its forward free end rebent into a spring-tongue, the latter having a laterally-offset upstanding arm engaging the thill-bolt, substantially as and for the purpose set forth.

20 2. In a thill-coupling, the combination of 25 an axle-clip having opposite bearing-ears, a thill-iron, a thill-bolt having a head at one

end and a reduced portion provided near the opposite end of the bolt, and a substantially U-shaped spring formed from a flat strap of metal bent intermediate its ends, one of the 30 sides of the spring being provided with bolt-openings, whereby the spring may be secured to the ends of the clip and the free end of said side being bent back upon itself to provide an antirattler-spring tongue located between 35 the bearing-ears and adapted to bear against the thill-iron, and the other side of the spring having its free end bent back upon itself and provided with an offset upstanding arm having a longitudinal slot inclined upwardly and 40 rearwardly and opening out through the upper end of the arm, said slot being adapted to receive the reduced portion of the thill-bolt, substantially as shown and described.

In testimony that I claim the foregoing as 45 my own I have hereto affixed my signature in the presence of two witnesses.

FREDERICK REESE.
